UNITED STATES PATENT OFFICE.

OTIS A. MYGATT, OF NEW YORK, N. Y.

COMPOSITE INCANDESCENT-LAMP BULB AND REFLECTOR.

SPECIFICATION forming part of Letters Patent No. 762,927, dated June 21, 1904.

Application filed January 29, 1904. Serial No. 191,138. (No model.)

To all whom it may concern:

Be it known that I, OTIS A. MYGATT, a citizen of the United States, residing at New York, in the county of New York and State of New York, have invented certain new and useful Improvements in Composite Incandescent-Lamp Bulbs and Reflectors, of which the following is a specification.

This invention relates to combined electric-lamp bulbs and reflectors composed wholly of glass.

The object of the invention is to produce a combined bulb and reflector each part composed of glass and forming when united a symmetrical whole of predetermined form; also, to provide an air-space for the equalization of temperature of the surfaces where the reflector covers the bulb proper; also, to provide a bulb which shall show no tip or protuberance in that part of the bulb outside the reflector, the exhaust or vacuum seal being covered by the reflector; also, to combine with a lamp-bulb a reflector having a like coefficient of expansion and contraction, which reflector shall rest on the bulb at its lower end or edge only and complete the symmetry of outline by covering a reduced part of the bulb; also, to provide a symmetrical form of bulb and reflector in which the light-rays reflected from usual forms of filament shall be directed to the illumination of a definite predetermined area with maximum beneficial effect; also, to provide a lamp-bulb and reflector which may be shipped as a single structure, the reflector acting as a guard or protector for the bulb; also, to improve the constructions and combinations above outlined, substantially as hereinafter indicated and claimed.

Figure 1 is a side elevation of a reflector and bulb forming together a generally spherical body when viewed externally. Fig. 2 is a vertical central section of the same. Fig. 3 is a side elevation of a reflector and bulb forming together a double conical body. Fig. 4 is a vertical central section of the same. Fig. 5 is a side elevation of a reflector and bulb in outward form of a peg-top. Fig. 6 is a vertical central section of the same. Fig. 7 is an elevation of a pear-shaped bulb and reflector, and Fig. 8 is a vertical central section of Fig. 7.

It has heretofore been common to connect a reflector of glass or other material to an electric-lamp bulb near the top or socket of the bulb, the reflector flaring out in conical or other form to partly cover the bulb; but usually the reflector has been of much greater diameter than the lamp-bulb. (See, for example, my Patent No. 705,426, July 22, 1902.)

In the patent of Goodchild, No. 634,295, of October 3, 1899, a reflector is described which envelops the upper end of an electric-lamp bulb and fits as a petticoat or jacket thereon, such reflector extending outwardly only a short distance from the lamp-bulb. Such a reflector is supported throughout by the body of the lamp-bulb, which it neatly fits.

In my Patent No. 732,211, of June 30, 1903, a flared prismatic glass reflector is shown resting on and supported by an electric-lamp bulb.

That part of an incandescent electric lamp which is at the bottom when the lamp is suspended is usually the most effective for illumination. Many constructions are known whereby the greater quantity of the light-rays is projected downwardly or away from the socket, such as by the making of special filaments, as well as by the provision of reflectors. In practice, however, it has been found that an approximately oval loop filament of one or more turns is most economical in construction and of greatest endurance, and such form of filament is generally employed. My construction of bulb and reflector especially adapts itself to such filaments, although other forms of filament may be used.

In Figs. 1 and 2 the bulb proper is of glass. The lower portion 1 of this bulb is substantially a hemisphere. Above the median portion or zone 2 the bulb is of reduced diameter, the sides being preferably concave, as at 3, and brought into the neck 4, where the metallic cap (covering the lamp-stem 5) is attached in any usual manner. The filament 6 is inserted in the bulb in usual manner and is preferably the common double oval loop. A prismatic glass reflector 7 of the form of about a semisphere is formed, the greatest diameter of said reflector being about equal to that of the largest part of the bulb. This glass reflector has external prisms 8 of the

character frequently described by me as double-reflecting prisms—that is, such prisms as reflect and throw back into the bulb the greatest practicable part of the light-rays which emanate therein. Such prisms are particularly described in my Patent No. 736,535, dated August 18, 1903, and illustrated in Fig. 5 of said patent. There is a space 9 between the bulb and the reflector 7, which is an air-space and prevents the excess of heat at this part. The bulb with the reflector applied presents the form of a sphere, with stem 5 at one end. The prisms 8 are in the form of lunes, extending from the stem to about the middle or largest diameter of the bulb.

The lower portion 1 of the bulb is preferably ground or etched on its outer surface, as indicated by shading, Figs. 1 to 4. Incandescent-lamp bulbs are usually blown in a mold, and the air is afterward exhausted, generally from the end opposite the stem, and a tip is left on this end when the lamp is sealed. Sometimes the bulb has been exhausted by other means, but such is more expensive than the tip exhaust. The tip is almost invariably at the end opposite the stem, for the reason that although objectionable in any place it interferes less with the symmetry of the bulb at that point than at any other.

Instead of providing the tip and seal of the lamp at the end opposite the stem I provide an exhaust-stem at some point, as 10, which is covered by the reflector 7. The exhaust-tube at this point may be of any usual construction, and the sealing may be effected in any usual way; but as the seal is covered from observation by the reflector much less care need be expended in the finishing of the seal than would be the case were this part to be exposed to observation. As the seal is on that part of the lamp which is least luminous, the actual amount of light obstructed thereby is very small. The seal is fully protected by the reflector.

Figs. 3 and 4 illustrate a lamp-bulb which externally appears in form of two cones with their bases joined, the upper cone being truncated where the stem is attached to the bulb. The lower part 11 of the bulb is of blown glass, as is the concave part 13, which is covered by the frusto-conical reflector 17. In this case, as in the preceding, the glass reflector is substantially covered externally with integral prisms 18, which are double-reflecting prisms. The lower edge 19 of the reflector is beveled to form a continuation of the lower or inverted cone, and the inner face of the reflector bears on the outside of the bulb at the outer circumference instead of resting its edge on an enlargement of the bulb, as in Fig. 2.

When the bulb is suspended, the reflector may generally be supported thereon by its own weight; but when inverted or when arranged to project light horizontally the re-

flector must be held in place on the bulb. As the reflector is generally stronger than the lamp-bulb, it may also serve as a protector therefor in shipment and storage if properly secured.

A convenient means for securing the reflector in place on the bulb is a ring or nut 20, which screws down on the threaded stem 5 and bears on the top of the reflector. This ring may be of metal, rubber, or other material which will not detract from the appearance of the lamp. Of course the metallic thimble on stem 5 may overhang the reflector (see Fig. 6) or may have small fins 22 turned out over the top of the reflector. Other means may be provided for holding the reflector on the bulb, or the reflector may be cemented at its lower edge to the bulb.

The coefficient of expansion and contraction of glass is nearly equal under changes of temperature; but as the thin glass of a lamp-bulb expands and contracts much more quickly than the heavier glass of a prismatic reflector the presence of an air-space prevents accident from unequal expansion.

In Figs. 5 and 6 the general principles of the construction of Fig. 1 are applied to produce a symmetrical lamp of peg-top form, and in Figs. 7 and 8 the same are applied to a pear-shaped form. In each instance the bulb and reflector together form a symmetrical whole in the outline of a definite and common figure without projections, and to external appearance the bulb and reflector might be integral. In each case, however, there is an air-space between the upper part of the bulb and the prismatic reflector. The reflector covers this air-space and preferably covers the exhaust-seal, which should be under the reflector.

The light-rays from the filament which have an upward tendency pass through the upper reduced portion of the bulb with little or no obstruction and encountering the prismatic reflector are directed back into and through the bulb and radiate at the lower surface of the bulb along with the rays directly transmitted in that direction. If the lower body of the bulb be frosted or ground, the light will be much softened and diffused.

As with other reflectors, the effective light in downward direction is nearly doubled. As the reflector is reduced to a minimum size, it is less in weight and in cost than would be a reflector having projections beyond the body of the bulb. As it is close to the bulb, it serves as a protector therefor, as has been explained.

Dust on the outer surface of the reflector does not interfere with its reflective power. As the reflector is generally above the bulb, it largely protects the illuminating-surface of the lamp from dust.

The prisms on the reflector do not entirely prevent the passage of light-rays. The outer surface of the reflector presents an attractive

but subdued brilliancy, and the uncovered body of the bulb gives a bright or a softened light, accordingly as it is of clear or frosted glass. The prismatic reflector should be of clear glass.

From the foregoing it will be perceived that both the reflector of the present invention and the lamp-bulb depart from usual constructions for the purpose of adapting them for use with each other as a composite whole. Reflectors of glass have generally been made heretofore with a collar or some means of support at the top or with a flared part at the lower extremity and have been adapted for use with many forms of lamps. Lamp-bulbs have been made of many forms, but not, so far as I am aware, with a reduced portion for the purpose of receiving a reflector which when added makes with the luminous portion of the bulb a symmetrical whole. Such a bulb I do not herein claim, broadly, as it is considered a separate invention.

What I claim is—

1. A compound incandescent electrical lamp bulb and reflector, consisting of a bulb of symmetrical outline as to its lower part and reduced diameter above, and a glass reflector having its lower edge and outer surface forming a continuation of the symmetrical outline of the bulb, and its body covering the reduced portion of the bulb.

2. A compound incandescent electrical lamp bulb and prismatic reflector of glass, the bulb having its lower portion of symmetrical form and its upper portion of reduced diameter, and the reflector having its lower edge resting on the bulb and its outer surface forming a continuation of the outline of the bulb, the reflector covering the reduced portion of the bulb.

3. An incandescent lamp bulb and reflector composed of glass, the bulb having its lower portion of symmetrical form and its upper portion of reduced diameter relatively thereto, and a reflector having its lower edge resting on the enlarged portion of the bulb, its body covering the reduced portion of the bulb, and its outer surface substantially covered

with reflecting-prisms and forming a continuation of the symmetrical body of the bulb. 50

4. The combination with a lamp-bulb having its upper body of reduced diameter and the exhaust-seal on this reduced part of its body, of an external reflector having its lower edge resting on the body of the bulb, and covering the exhaust-seal, said reflector forming a symmetrical continuation of the enlarged portion of the lamp-bulb. 55

5. The combination with an incandescent electrical lamp bulb having its upper body 60 portion of reduced diameter and provided with a stem, of a prismatic-glass reflector having its lower edge resting on the enlarged portion of the bulb, said reflector mechanically secured to said bulb by suitable means. 65

6. The combination with an incandescent electrical lamp bulb having its lower body of symmetrical form and its upper portion of reduced diameter, of a reflector of prismatic glass having its lower edge bearing on the enlarged body of the bulb, and its outer surface forming a continuation of the symmetrical portion of the bulb, and means for securing the reflector to the bulb. 70

7. The combination with an incandescent- 75 lamp bulb having its upper body portion of reduced diameter, of a glass reflector covering said reduced portion and having its lower edge resting on the bulb, a stem on the bulb, and means on the stem for holding the reflector. 80

8. The combination with an incandescent-lamp bulb having its lower portion symmetrical and externally frosted and its upper portion of reduced diameter, of a glass reflector having its lower edge resting on the 85 bulb and its outer surface forming a continuation of the symmetrical outline of the bulb, said reflector covered externally by integral reflecting-prisms.

In testimony whereof I affix my signature in 90 presence of two witnesses.
